Inventor

By Attorney *Arnold*

UNITED STATES PATENT OFFICE.

EDWIN R. GILL, SR., OF YONKERS, NEW YORK.

CURRENT-RECTIFYING UNIT AND METHOD OF PREPARING THE SAME.

Application filed September 25, 1926. Serial No. 137,670.

The present invention has relation to the treatment of rectifying "crystals", so called, whether natural or synthetic, whereby the slow and clumsy groping for the so-called sensitive spot is eliminated, making it possible to instantly locate and distinguish by the eye the position, form and limits of the sensitive portions of any "crystal" or mass of crystals.

My invention also has reference to a complete mode of treatment and preparation of rectifying units, as well as to the unit as completed.

In my applications for United States patent, filed April 13th, 1926, Serial Numbers 101,608 and 101,609 I have described a mode of preparing rectifying apparatus involving what I have termed the "development" of the latent rectifying power of "crystals" whether natural or synthetic, and in my United States application filed August 13, 1926, Serial Number 129,101, I have described a further advance in the art of developing this latent power, together with a novel mode of preparing efficient rectifying units.

These patent applications had reference to the development or increase of rectifying efficiency of these "crystals" under a conducting point preferably of silver, and the development as there described is carried on under such a point after the sensitive spot on the "crystal" is located and the conducting point is applied to it.

Hitherto it has been found necessary to grope blindly over the "crystal" surface to find the one or more sensitive spots on its surface by moving a conducting point or needle over said surface while observing the behavior of a suitable current indicator in circuit with the needle and the "crystal". This is not only a slow process, but, even when a sensitive spot is found on a "crystal", one cannot be sure that the best spot has been located. Moreover it is frequently found that the "crystal" tested is substantially worthless as a rectifier, and all the time spent in thus groping over its surface proves to have been wasted.

I have made the important discovery that, by a simple, rapid and inexpensive method of "surface development" analogous to the point development above mentioned, all of the surfaces of a "crystal" mass may be made to reveal to the eye the relative rectifying powers of the various portions exposed.

This makes it possible to pick out at a glance which are the valuable "crystal" masses available in a given group, as well as to identify what portions of a selected mass, either crude or prepared for use, should be brought into circuit when rectification is desired. Thus this "surface development" may be resorted to, either as a preliminary test on crude masses, to determine rapidly and certainly what portions thereof should be retained for use, or at any stage in the preparation of a finished rectifying unit.

Broadly stated the surface development in question consists in moistening the surface with water or dilute acid, preferably the latter, while passing an electrical current through the same.

Inasmuch as I have had marked success with native iron pyrites, and as the present invention relates partly to the finishing of a commercial rectifying unit, I shall hereinafter describe my process in its preferred embodiment with reference to the preparation of a finished unit made of pyrites. It is to be understood, however, that my broad invention is not limited either to this material or to this particular purpose.

In the accompanying drawings Figures 1, 3 and 4 are perspective views of a preferred form of rectifying unit in different stages of preparation, and Figure 2 is a diagram illustrative of the preferred process of "surface development".

As already described in my earlier patent application, Serial Number 129,101, I first cut out of a mass of pyrites or its equivalent a cube, such as is shown in Figure 1 at 10. This will have a bright golden glitter which is substantially uniform over the entire surface, as is indicated in Figure 1 by the absence of all shading between the outlines of the cube. The eye cannot distinguish which portions, if any, of these surfaces are useful in rectification of an alternating current.

In order to impart the "surface development" above mentioned I may proceed as follows. A flat plate 11, preferably of carbon is moistened, preferably with dilute sulphuric acid of the strength commonly used in secondary battery cells and the cube 10 is set down upon it. The top of the cube is then moistened in the same manner, and a flat bottomed conductive contact piece 12, preferably of carbon is laid on the cube.

At 13 and 14 are shown wires representing the two sides of an electric circuit. This may be either direct current or alternating current. I have also used direct superimposed upon alternating current. I find alternating current best for this purpose, however. The carbon plate 11 is laid upon a metal plate 15 which is connected by the wire 16 to one side 14 of the current supply, or any means may be employed to bring the plate 11 into circuit. The wire 17 connects the carbon contact piece 12 with the opposite wire 13.

While current is thus passing through the moistened surfaces of the cube 10, the surfaces of the conductors 11 and 12 may be made to rub across the cube to insure uniform and efficient contact and to expedite the process.

The amount of current used and the time employed will vary with circumstances. With a cube of pyrites a quarter of an inch across I have obtained excellent results with an alternating current of six volts by continuing the process for a few seconds—say ten to twenty-five.

This step in the process being finished, the cube is carefully washed and preferably dried by evaporation, after which the process may be repeated until all six faces of the cube have been "developed".

Figure 3 shows in a conventional form a picture that may be taken to roughly exemplify the appearance of the faces of the cube after the treatment above described; it being understood, of course, that in actual practice the markings and shadings will vary in form and location indefinitely.

For purposes of example the sides of the cube have been represented in three shades, pure white, light grey and dark grey. The pure white represents a steely, hard surface which is bright in appearance and conductive, but without appreciable rectifying power. There will also be observed patches represented by the dark grey which are actually quite dark and lack luster, somewhat resembling soot. These portions have a certain degree of rectifying power, but they are very inferior to those parts of the surfaces conventionally shown in Figure 3 by the light grey shading.

These have a dull silvery aspect and invariably exhibit the maximum of rectifying power. Of course, the sharp limits between these various parts as shown in the figure are seldom found in practice. The various surfaces may shade off into one another; but as a rule, the steely relatively useless portions are rather sharply defined.

When the entire cube has been "developed" in this way to make it reveal its true properties to sight, the various faces are inspected to determine which will give the

best results. Glancing at Figure 3, for instance, it will be seen that the top surface has by far the greatest area of light grey shading, which represents the highly efficient rectifying area.

This side is therefore chosen at a glance and the other five faces are thereupon further treated. These are first abraded by rubbing on emery cloth or otherwise grinding. This has three uses. It increases the conductivity of these faces; it destroys any rectifying activity which might act counter to the effect desired from the chosen face; and it fits these faces to be electroplated, preferably with copper.

This electro-plating is the next step, being accomplished in a well known manner; the chosen active face being protected and kept undisturbed and unrubbed so far as possible.

The finished unit is thus completed and presents the appearance shown in Figure 4, wherein the sides other than the active top are shown covered with a copper coating.

When this unit is placed in operative position under the conducting point which conveys current to it, a further "point development" may be obtained, which increases its efficiency. This is described in my earlier application Serial Number 129,101.

The process above described may be indefinitely varied and may be applied to rectifying materials of various kinds in any stage of use and any condition without departing from my invention. It is also to be understood that the apparatus herein described exemplifies merely the principles upon which commercial apparatus should be preferably constructed in carrying out my process.

What I claim is—

1. The process of treating the surface of a current rectifying substance to make visible the more sensitive areas, which consists in moistening said surface and passing an electric current through said surface.

2. The process as in claim 1 wherein dilute sulphuric acid is used to moisten the surface.

3. The process as in claim 1 wherein two opposite surfaces are moistened and current is passed through both.

4. The process as in claim 1 wherein alternating current is used.

5. The process of treating the surface of a current rectifying substance to make visible the more sensitive areas which consists in moistening the surface and subjecting the same to friction while passing an electric current therethrough.

In testimony whereof I have hereto affixed my signature on this 24th day of September, 1926.

EDWIN R. GILL, SR.
